UNITED STATES PATENT OFFICE

DAVID D. GORDON, OF CHICAGO, ILLINOIS, ASSIGNOR TO ECONOMY FUSE AND MANUFACTURING COMPANY, OF CHICAGO, ILLINOIS, A CORPORATION OF NEW YORK

ADJUSTABLE CANDLE SOCKET MOUNTING

Application filed March 23, 1927. Serial No. 177,481.

The present invention relates to adjustable candle socket mountings.

More particularly, the present invention relates to electric devices of the type known in the art as candle sockets, commonly employing a cylindrical sleeve, simulating a candle. Said sleeves come of varying lengths and require the carrying in stock of different sizes of holding means for holding the usual socket for receiving the electric lamp.

Candle socket constructions frequently embody a switching mechanism for switching on and off the electric lamp associated with the candle socket mechanism. The means for supporting the socket containing the electric lamp and the switching mechanism should be rotatably adjustable independently of the vertical adjustability of the socket switching mechanism.

20 An object of the present invention is to provide an adjustable candle socket mounting which permits a very large range in longitudinal adjustment of the light socket relative to the electric fixture with which it is associated.

25 A further object is to provide an adjustable candle socket mounting which is easy to assemble and which, therefore, simplifies the work of the artisan or other person installing said candle socket mounting.

30 A further object is to provide a candle socket mounting having a wide range of adjustability in a longitudinal direction and which is also readily adjustable in a circumferential direction.

35 Further objects will appear as the description proceeds.

Referring to the drawings—

40 Figure 1 is a longitudinal sectional view of a candle socket mounting embodying the principles of the present invention;

45 Figure 2 is also a longitudinal sectional view of the structure shown in Figure 1, but taken at right angles to the plane shown in Figure 1;

Figure 3 is a view in side elevation of a clamping member forming a part of the structure illustrated in Figures 1 and 2; and

50 Figure 4 is a sectional view taken along

the plane indicated by the arrows 4—4 of Figure 1.

The numeral 10 indicates a conduit for electric wires 11—11, which may constitute two wires of an electric house wiring system. Said conduit 10 is part of an electric fixture, as for example, a chandelier, wall bracket, or other fixture. Secured to the conduit 10, near to the outer extremity thereof, is the cup 12 having the cylindrical wall 13 and the shoulder 14. The numeral 15 indicates a sleeve member located within the wall 13 of the cup 12 and resting upon the shoulder 14.

The numeral 16 indicates a clamping member secured to the conduit 10 at the extremity thereof. Said clamping member comprises the two gripping members 17—17 and the intermediate portion 18. The extremity of the conduit 10 and the intermediate portion 18 of the clamping member 16 may have cooperating screw-threads whereby said clamping member 16 may be rigidly positioned upon said conduit 10.

The clamping member 16 provides adjustable holding means for a lamp socket indicated by the numeral 19. Said lamp socket 19 is adapted to receive the lamp 20 and is provided at its other extremity with a cylindrical shank 21, adapted to be gripped by the gripping members 17—17 of the clamping member 16.

The lamp socket 19 is provided with a switching mechanism indicated by the numeral 22, which switching mechanism is illustrated as being of the pull chain variety, a pull chain 23 being illustrated, which pull chain extends through an aperture 23' in the cup 12.

The numeral 24 indicates a sleeve adapted to encircle the gripping members 17—17. Said sleeve 24 may have a substantially cylindrical interior conformation, or may be slightly conical to conform to the tapering conformation of the gripping members 17—17. Said gripping members 17—17, which may be formed of sheet metal, are preferably rounded, so that in cross-section they take the form of arcs of a circle.

One of the gripping members 17 is provided with a plurality of spaced struck-out

portions or projections 25—25, best illustrated in Figure 3. The inner surface of the cylindrical member 24 is provided with a recess 26 adapted to receive selectively one or another of the buttons 25.

Disposed diametrically opposite to the recess 26 in the cylindrical sleeve 24 is the screw-threaded aperture 27 containing the set screw 28, which set screw is adapted to engage the corresponding gripping member 17.

Located preferably, though not necessarily, in each of the gripping members 17—17, a short distance above each button 25 (with the exception of the uppermost button 25), is the saw-mark or depression 29.

The mode of operation of the present invention will be clear without detailed explanation. It will be clear that the clamping member 16 may be screwed down upon the conduit 10, whereby to be rigidly secured in position upon said conduit 10. The shank 21 of the lamp socket 19 will be positioned between the extremities of the gripping members 17—17, the set screw 28 being loosened

slightly to permit the ready insertion of said shank 21 within said gripping members 17—17. The uppermost projection 25 will be disposed within the recess 26 of the inner wall of the sleeve 24, and the set screw 28 will be turned home to hold the gripping members 17—17 in tight engagement with the shank 21 of the lamp socket 19.

It will be understood that the invention permits a considerable range of adjustment in the position of the lamp socket 19 by reason of the fact that the shank 21 may be gripped at any preferred region throughout the length of said shank 21. Moreover, the switching mechanism 22 may be disposed at the proper angle to allow the pull chain 23 to hang in a substantially vertical plane and to be disposed at any preferred position relative to the conduit 10.

By reason of the plurality of projections 25 and by reason of the saw marks or depressions 29—29, a greatly increased range of adjustability is had, due to the fact that the gripping members 17—17 may be cut off at or near any one of the regions 29—29, whereby said gripping members may be varied in length. The advantage of this construction will be obvious. The electrical artisan need carry with him only one size of clamping member 16. If the job which he has at hand calls for a fitting for a relatively short sleeve member 15, he can readily cut off the gripping members 17—17 at or near the proper regions, having available at the gripping extremities of said members 17—17 a button 25 for holding the sleeve 24 in position.

By reason of the present invention, therefore, the number of clamping members 16 which must be stocked by the electrical supply house in order to meet the demands of the trade is reduced to a minimum.

The present invention provides a firm gripping means which is simple to install and which effectually meets the demands of ordinary service conditions.

Though a preferred embodiment of the present invention has been described in detail, many modifications will occur to those skilled in the art. It is intended to cover all such modifications that fall within the scope of the appended claims.

What is claimed is—

1. An adjustable candle socket mounting comprising a clamping member having a pair of gripping portions, a lamp socket having a shank adapted to be gripped by said gripping portions, a sleeve encircling said gripping portions, one of said gripping portions and said sleeve being provided with a cooperating projection and recess for positioning said sleeve longitudinally with relation to said clamping member, and screw means carried by said sleeve for holding said gripping portions in gripping relationship with said shank.

2. An adjustable candle socket mounting comprising a clamping member having a pair of gripping portions, a lamp socket having a smooth cylindrical shank adapted to be gripped by said gripping portions, a sleeve encircling said gripping portions, one of said gripping portions and said sleeve being provided with a cooperating projection and recess for positioning said sleeve longitudinally with relation to said clamping member, and screw means carried by said sleeve for holding said gripping portions in gripping relationship with said shank.

3. An adjustable candle socket mounting comprising a clamping member having a pair of gripping portions, a lamp socket having a shank adapted to be gripped by said gripping portions, a sleeve encircling said gripping portions, one of said gripping portions being provided with a plurality of projections spaced longitudinally of said clamping member, said sleeve being provided with a recess adapted to receive selectively any one of said projections whereby to position said sleeve at predetermined regions relative to the length of said clamping member, and screw means carried by said sleeve for holding said gripping portions in gripping engagement with said shank.

4. In lamp socket mechanism, a conduit for electric wires, elongated holding means mounted on said conduit, an electric socket, a stem carried by said socket, said stem having a smooth cylindrical portion adapted to be located between said holding means and having a rotary and axially slid able bearing relationship therewith, ring means encircling said holding means for holding same in gripping relationship with said stem, said holding means being adapted to be freed sufficiently from said stem to permit longitudinal sliding

movement of said stem between said holding means independently of any rotative movement of said stem, said holding means being provided with a plurality of spaced projections, said ring means being provided with a recess for selectively receiving any one of said projections, and screw means carried by said ring means for maintaining said holding means for gripping engagement with said cylindrical portion.

5. In a candle socket, a candle cup, a candle sleeve, an electric socket within said sleeve, ratchet mechanism for controlling said socket, elongated holding means, a smooth cylindrical stem for supporting said socket and said ratchet mechanism, a pendant member for operating said ratchet mechanism, said candle cup being provided with a hole for permitting the passage therethrough of said pendant member, ring means cooperating with said holding means for holding said stem in adjusted position both rotatably and longitudinally relative to said holding means, said holding means being adapted to be freed sufficiently from said stem to permit longitudinal sliding adjusting movement of said stem relative to said holding means independently of any rotative movement of said stem, said holding means being provided with a plurality of spaced projections, said ring means being provided with a recess for selectively receiving any one of said projections, and screw means carried by said ring means for maintaining said holding means for gripping engagement with said stem.

Signed at Chicago, Illinois, this 18th day of March, 1927.

DAVID D. GORDON.
